Application April 24, 1926, Serial No. 104,407
Renewed July 30, 1932

16 Claims. (CL. 274—21)

This invention relates to phonograph machines, and in a more specific aspect to machines for recording or reproducing dictation, or both, such machines being known as commercial phonographs.

An object of this invention is to provide means associated with the power operated driving means of such machines for mechanically performing functions heretofore performed by force 10 extraneous to said driving means.

Another object is to provide means whereby the operation of said mechanical function-performing means may be manually controlled, and preferably this may be done from a point remote 15 from the machine.

A further object is to provide an improved back-spacer mechanism for phonographs.

A still further object is to provide a back-spacer mechanism for phonographs which is operated by a part of the machine which constantly operates while the machine is in use, said back-spacer mechanism being controlled preferably from a point remote from the phonograph.

Another object of this invention is to provide 25 a manually operable remotely located controlling device and a bracket therefor, which device may be easily detached by hand from the bracket which itself may be detachably connected to a typewriter frame.

Another object of this invention is to transmit 30 the power manually applied to the manually operable controlling device to the mechanism which it operates on the frame of the phonograph by a flexible connection, such as an air-hose.

Other features and advantages will herein-after appear.

In the accompanying drawings, which illustrate 40 the present invention in the form at present preferred—

Figure 1 is a view of a typewriting machine, and a phonograph of the transcriber type located along side of the typewriter, the connections between the manually operable part on 45 the typewriter and the phonograph being shown.

Fig. 2 is a perspective view of the top portion of the phonograph, showing the present invention as applied thereto.

Fig. 3 is a bottom view of the sound-reproducing means of the present invention.

Fig. 4 is a transverse sectional view of the sound reproducing means, substantially on the line 4—4 of Fig. 3.

Fig. 5 is a side elevation of a phonograph, the 55 mandrel driving pulley being in section on the

line 5—5 of Fig. 6 so as to show the power-actuated means for operating the back-spacer mechanism.

Fig. 6 is a top view showing a portion of the mechanism shown in Fig. 5, and showing the 60 driving pulley partly in section.

Fig. 7 is a front elevation of the portion of the mechanism shown in Figs. 5 and 6.

Fig. 8 is a sectional view of the manually operated control which is mounted on the frame 65 of the phonograph, the section being substantially on the line 8—8 of Fig. 1.

Fig. 9 is a sectional view of the manually operable part which controls the operation of the actuating mechanism for the back-spacer, the 70 section being substantially on the line 9—9 of Fig. 1.

Fig. 10 is a perspective view of the bracket part for the manually operable part.

Fig. 11 is a detail view of part of the sound- 75 reproducing means.

Fig. 12 is a side sectional view of the back-spacer mechanism.

While the commercial phonograph shown in the accompanying drawings is of the transcribing type, 80 yet the invention is not limited to use in connection with this kind of a machine, but is also applicable to other machines such as dictating machines and combined dictating and transcribing machines; also to other phonographs.

Referring to Fig. 1, the machine shown in the accompanying drawings comprises a base 10 containing a driving motor 11. As may best be seen in Fig. 2, the top of the casing is constituted by a table 12 having formed integral therewith a housing 13 for supporting a mandrel 14 adapted to carry a record 15, which is to be reproduced.

The table 12 also has vertical standards 16 and 17 between which there is mounted a guide rod 19, (Fig. 12) adapted to control the traveling movements of a sound-box carriage 20 over a record 15 to reproduce the sound recorded upon the record, which traveling movements forwardly are controlled by the rotation of a feed-screw 21 which is engaged by a nut 21' mounted on the 90 carriage 20. Again referring to Fig. 2, the mandrel 14 is mounted upon a shaft on whose end a movable clutch member 22 is provided. This clutch member 22 is adapted to cooperate with a clutch member 23 secured to a pulley 24 which is 100 constantly rotated while the machine is in use by the motor 11 through a belt 25.

In using the machine, the clutch member 22 is moved into and out of engagement with the continuously operating clutch member 23 by the user 110

of the machine through mechanism not shown and of no particular consequence in connection with the present invention. Suffice it to say, that even when the clutch member 22 is disengaged 5 from the clutch member 23, the pulley 24 continues to operate, being at all times positively driven through the belt 25 by the motor 11.

It frequently occurs in the use of the machine that the operator desires to revert to a portion of 10 the record just passed to verify the transcription or to again listen to something which was not entirely clear. To facilitate this, transcribing machines have heretofore been, and the machine of this invention is, provided with back-spacing 15 means comprising a lever 26 having a hub 27 supported by the sound-box carriage 20 and carrying a pawl 28 adapted to cooperate with a toothed rack 29 supported by the standards 16 and 17 directly above the guide rod 19.

20 When the lever 26 is depressed, the pawl 28 engages the rack 29 and forces the carriage backwardly, i. e. towards the left, in Fig. 2. The same operation also raises the nut 21' from the feed-screw 21 to free the carriage therefrom for the 25 back-spacing movement.

Mounted in the carriage 20 is a sound-box 30 which, as usual, contains a diaphragm 31, (see Figs. 3 and 4) and a stylus 32 mounted in a pivoted lever 33 carried by a weighted support 34 pivotally mounted on a pivot rod 35 carried by a bracket 36 mounted on trunnions 37 for movement in a plane at right angles to the plane of movement of the support 34 on the pivot 35. The pivot 35 and the trunnions 37 permit the stylus 32 to have free lateral and vertical movements on the record within the limits of a guide 38 engaged by a pin 39 carried by the support 34. In accommodating itself to records of various thicknesses and to inequalities in the record surface, the 40 stylus 32 with its support 34 moves up and down on the pivot 35, and to permit free tracking of the record they move horizontally about the trunnions 37. The stylus lever 33 is connected to the diaphragm 31 by a wire 40.

45 In addition to the function above described, the horizontal pivot 35 of the weighted support 34 allows the latter with the stylus lever and stylus to be raised from record-engaging position when desired. To do this, when it is desired to move 50 the sound-box carriage a relatively long distance along the record, either forward or backward, or when it is desired to change records, the weight lever 34 is provided with a depending arm 85, see Figure 12, adapted to be engaged by an arm 86 carried by a carriage release or sound-box conditioning lever 87. This conditioning lever is so arranged that when the operator raises its forward end, its rearwardly extending arm 86 engages arm 85 of the weighted support 34, and 60 raises the latter with the stylus from the record surface. At the same time, the arm 86 engages the upper portion 88 of the feed nut 21', to disengage the nut from intermeshing relation with the feed screw 21. For more complete description 65 of the backspacing mechanism, sound-box construction and actuating means for the locking lever 42, reference should be made to the patent to T. H. MacDonald, No. 1,030,740, patented June 25, 1912, and to the patent of the present applicants, No. 1,726,574, patented September 3, 1929, the application of which was co-pending here-with.

In order that the back-spacing movements of 75 the stylus will always be uniform regardless of the lateral position in which the stylus might be

located when the back-spacing operation is commenced, improved means are provided by the present invention for locking the stylus and its support 34 against lateral or free tracking movements with respect to the carriage during the back-spacing operation. This means, in the form shown, comprises a locking lug 41 carried by the pivoted bracket 36 on which the support 34 is mounted, and a movable locking device comprising a lever 42 pivoted on a screw 43 mounted in the sound-box 30 and carrying a notched wheel or other member 44 cooperating with the locking lug 41. The locking lever 42 is provided with a depending lug 45 normally located in the range of an arm 46, (Fig. 12) pivotally mounted on the carriage 20 and actuated through a spring 47 when the nut 21' is raised upon the depression of the backspace key 26. It will be understood that not only is the arm 46 actuated to bring the notched wheel on the locking lever 42 into engagement with the locking lug 41 when the feed-nut 21' is raised by operation of the backspace lever 26, but that it is similarly actuated to perform the same function when the feed-nut 21' is raised by operation of the sound-box control lever 87.

With this form of device, the stylus need not be raised from the record-surface during the back-spacing movement, but is allowed to skid or glide over the surface.

It will be noted from an examination of Fig. 11, that the guide member 38 at its upper portion is V-shaped so as to centralize the weighted support 34 and the stylus 32 with respect to the sound-box each time the lever 34 is raised to its upper limit of movement by means of the sound-box conditioning lever 87, an operation performed when the stylus is raised to permit removal or replacement of records or when shifting the carriage by hand. This centralizing movement of the weighted lever 34 upon being raised could not be effected because of the engagement of the locking lug 41 with the notched member 44, unless some provision were made to permit relative movement between the latter and the lever 42 which supports it. This is accomplished by the present invention by making the member 44 in the form of a notched wheel pivotally mounting it on the lever 42 and frictionally holding the notched wheel 44 (Figs. 3 and 4) against movement during the back-spacing operation by a spring 48. The friction produced by this spring is sufficient to hold the wheel 44 against movement during back-spacing operation, but insufficient to prevent centralizing movement of the weighted lever 34 when the latter is raised by means of conditioning lever 87. The lever 42 may swing by its own weight to inoperative position when the actuating arm 46 is moved back by the return of the manually operated lever 26.

Since the person using the machine is usually located at some distance from the machine, receiving the sound from the sound-box 30 through a flexible tube 49, (Fig. 1) leading to hearing devices 50, it is sometimes inconvenient to reach forward to the machine to operate the back-spacer key lever 26. To avoid the necessity of doing this, the present invention provides means operated by the motor 11 for actually performing the back-spacing operation and so arranged that this means can be controlled from a typewriting machine 51 or other point remote from the phonograph by an easily operated device, hereinafter described.

The means operated by the motor 11 for actually performing the back-spacing operation

80

105

110

115

120

125

130

135

140

145

150

comprises a universal bar or bail 52 journalled in the standards 16 and 17 and normally underlying an arm 53 (Figs. 2 and 12) secured to the back-spacer key lever 26. Hence, when the bail 5 is rocked the back-spacer key lever will be depressed and the carriage will be returned one step by the engagement of the pawl 28 with the toothed rack 29. The bail 52 extends through the standard 17 and has an operating arm 54 at its protruding end (see Fig. 5).

The power for operating the bail 52 may, in accordance with this invention, be taken directly from the motor 11, but preferably it is taken from the pulley 24 which is driven by the motor through the belt 25. For this purpose, the hub of the pulley 24 is provided with cams 55 adapted to engage an interponent 56 (Figs. 5, 6 and 7) pivotally mounted on a stud 57 secured in the standard 17. The interponent 56 is coupled with a control lever 57 by a pin-and-slot connection 58, and the lever 57 is provided with an anti-friction roller 59 adapted to engage a flat surface 60 on the arm 54 secured to the bail 52. When the end 61 of the interponent 56 is in the path of the cam 55, the interponent will, by engagement with the cam 55, be rocked, rocking with it the control lever 57 which in turn operates the bail 52 through the arm 54. This operation would be repeated indefinitely so long as the end 61 were permitted to remain in the path of the cam 55.

However, the end 61 of the interponent 56 is not always in the path of the cam 55, but is normally in the position shown in Fig. 6, out of the path of the cams. It is held in the latter position by a trip-lever 62 having a cam surface 63 arranged to be engaged by a lug 64 on the interponent 56. The trip-lever 62 is pivotally mounted on a stud 65 and when released from engagement with the lug 64 by means herein-described, permits the end 61 of the interponent 56 to be swung into the path of the cams 55 by a spring 66 carried by a stud 67 in the control lever 57. This pivotal or swiveling movement of the interponent 56 is permitted by its loose mounting on the stud 57, and it is kept in coupled arrangement with the control lever 57 during this swiveling movement by the pin-and-slot connection 58 and the stud 67.

After each operation of the interponent 56, it is automatically rendered inoperative by being moved out of the range of the cams 55 by the trip-lever 62, which returns to its normal position after the lug 64 has been swung down and is then in position to engage the lug 64 with its cam surface 63 upon the rising movement of the lug which causes the interponent to be pivoted or swivelled so that its end 61 will be moved away from the cam 55.

Of course, if the trip lever 62 is held inoperative by any means, the interponent will not be made ineffective or inoperative, and the back-spacing operation will be repeated step-by-step until the carriage 20 reaches the limit of its movement, or so long as there are teeth on the rack 29 for the pawl 28 to engage.

While the cams 55 and the interponent 56 operate the bail 52 to back-space the carriage, the bail, the interponent 56 and its control lever 57 are all returned, by a single spring 68a connected by the arm 54 of the bail, to their normal positions controlled by an adjustable stop 68b secured to a bracket 68 embracing the standard 17. Preferably, a leather bumper 70 is mounted in the control lever 57 so as to reduce the noise of operation of the device.

Thus it will be seen that the present invention provides a back-spacing device operated by the power of the motor and one which may back-space the carriage one step or any number of steps so long as the trip-lever 62 is held inoperative. 80

Referring to the lower right-hand corner of Fig. 5, and to Fig. 8, for the purpose of controlling the trip-lever 62 from a point remote from the machine, the present invention provides a cylinder 71 mounted in the bracket 69 and having a piston 72 which has a pin 73 adapted to engage an arm 74 on the trip lever 62. When the piston is moved outwardly of the cylinder by the pressure of air in a manner hereinafter described, the pin 73 rides on the arm 74 until it engages a dwell 75 on the arm which is its normal operated position, and in which position the upper end of the trip-lever 62 is disengaged from the lug 64 on the interponent 56. 90

The cylinder 71 has secured thereto in communication with its interior a flexible tube 75 whose other end is threaded into a similar cylinder 76 (Figs. 1 and 9) carrying a piston 77 on whose end is mounted a finger-piece 78, the arrangement being such that when the piston 77 is moved inwardly of the cylinder against the tension of a spring 79 by the finger-piece 78, the air is expelled from the cylinder and forced through the flexible tube 75 into the cylinder 71, 100 and this excessive air forces the piston 72 outwardly of the cylinder to operate the trip lever. The parts are held in these positions so long as the finger-piece 78 is held depressed, but as soon as the finger-piece 78 is released, the spring 79 110 returns it and its piston 77 to normal position creating a partial vacuum in the cylinder 71 which in turn withdraws the piston 72 from engagement with the dwell on the trip lever which allows the trip lever to return by gravity to its normal position. 115

In order that the manually operable control device comprising the cylinder 76, the piston 77 and the finger-piece 78 may be securely mounted on a typewriter frame and yet be detachable therefrom, the piston 77 is mounted in a bracket (Figs. 9 and 10) having a U-shaped clamping portion 80 adapted to embrace a part of the frame of the typewriter and to be clamped thereto by a set screw 81. 125

To further permit the manually operable device comprising the cylinder 76, the piston 77 and finger-piece 78 to be easily and quickly detached from its support on the typewriter, the bracket is provided with a flicor or base 82 and a pair of arms 83 adapted to encircle the cylinder. The arms 83 are spaced from each other and extend sufficiently to permit the nipple 84 on the cylinder 76 to pass therethrough, and they are spaced from the floor or base 82 sufficiently to permit the nipple 84 to be locked under the arms 83 when the cylinder is partially rotated in either direction from the position in which it was inserted into the bracket. 135

Thus it will be seen that the bracket, provided by the present invention, may be used on either the left hand or the right hand side of the typewriter, and no matter on which side of the machine it is used, the flexible tubing connection 75 may be arranged either to the right or left as desired. This simple detachable connection between the manually operable part 78 and the supporting bracket is extremely advantageous since it enables the manually operable part to be quickly and easily removed from its support on 140 145 150

the typewriter when it is desired to close the desk of the typewriter, for instance, or for any other purpose.

5 Variations and modifications may be made within the scope of this invention and portions of the improvements may be used without others.

Having described the invention, what is claimed as new and for which it is desired to obtain Letters Patent, is:

10 1. In combination, a stylus; a sound-box; a frame; a carriage movably mounted on said frame; means for mounting the stylus in the sound-box and adapted to permit the stylus to have free tracking movement, said means comprising a pivoted bracket; means for mounting the sound-box on the carriage; a lever pivoted on the sound-box; and a notched wheel mounted on said lever and adapted to engage said bracket when the carriage is spaced along the frame to lock the stylus against free tracking movement, said notched wheel being frictionally held against undesired movements.

20 2. In combination, a frame; a record-support; means for driving said record-support; a sound-box carriage mounted on the frame for to and fro movement; a sound-box in said carriage; a sound-box stylus mounted for tracking movement relative to the record support; means associated with said driving means for automatically backspacing the sound-box carriage while the stylus remains in engagement with the record-surface; and means actuated by the back-spacing means when it is operated positively to prevent free tracking movement of the stylus during back-spacing movement of the carriage.

30 3. In combination, a frame, a sound-box carriage mounted on the frame for to-and-fro movement, power means for driving said carriage, backspacer mechanism actuated by said power means intermittently operated from a position of rest to move the carriage backwardly step-by-step, a stop for determining the position of rest of said mechanism, and resilient means coacting with said stop to absorb the noise and shock incidental to the intermittent action of said mechanism.

40 4. In combination, a frame; a sound-box carriage mounted on the frame for to and fro movement; power means for driving said carriage; a back-spacer mechanism movable from a position of rest to move the carriage backwardly; an actuator for said back-spacer operated by said power means; and means comprising an adjustable stop to determine the position of rest of said back-spacer mechanism.

50 5. In combination, a stylus, a sound-box, means comprising a bracket for mounting the stylus in the sound-box, said bracket being movably mounted to permit the stylus to have free tracking movement, a sound-box carriage, a sound-box conditioning lever and a backspacing lever on said carriage, means on the sound-box to centralize the stylus relatively thereto when the conditioning lever is operated, a locking lever pivoted on the sound-box, a notched wheel mounted on said locking lever, means for causing said locking lever to engage said bracket when either the backspacing lever or the sound-box control lever is manipulated and means for resiliently resisting movement of said wheel relatively to said locking lever.

60 6. In combination, a record-support, a sound-box carriage mounted for to and fro movement relatively to said record-support, power means for producing carriage movement, a sound-box

in said carriage, a sound-box stylus mounted for tracking movement relative to said record-support, means actuatable by said power means for automatically backspacing the carriage step-by-step while the stylus remains in engagement with the record surface, and means actuated by the backspacing means when it is operated positively to prevent free tracking movement of the stylus during backspacing movement of the carriage.

80

85

7. In combination, a record-support, a sound-box carriage mounted for to and fro movement relatively to said record-support, power means for producing carriage movement, a sound-box in said carriage, a sound-box stylus mounted for tracking movement relative to the record-support, means actuatable by said power means for automatically backspacing the carriage step-by-step a predetermined extent at each step while the stylus remains in engagement with the record surface, and means actuated by the backspacing means when it is operated positively to prevent free tracking movement of the stylus during backspacing movement of the carriage.

90

95

8. In a phonograph, in combination, a record-support, power-operating means therefor, a stylus, a sound-box, stylus mounting means mounted on said sound-box for movement in two planes normal to each other to permit the stylus to be moved toward and from the side of a record carried by said record-support and also to permit free tracking movement of said stylus relatively to said record-support, a carriage for supporting said sound-box, a sound-box conditioning means comprising a manually operable lever and stylus centralizing means, an automatic backspacing means operable by said record-support operating means to move the carriage step-by-step a predetermined extent at each step, a lever pivoted on the sound-box, and a notched wheel frictionally held on said lever and adapted to engage said stylus mounting means when the automatic backspacing means is operated and hold said mounting means in substantially the same position relatively to the sound-box that it occupied when backspacing began, and yet allow centralization of the stylus relatively to the sound-box when the sound-box conditioning means is operated.

100

105

110

115

120

9. The combination in a phonograph of a frame, a carriage movably mounted on said frame, a record-support, a stylus, a stylus mounting on said carriage freely movable relative to said carriage, power-actuated means for spacing said carriage along the frame and the record-support, and means actuated by said power-operated means positively to engage the stylus mounting to prevent free movement of the stylus relatively to said carriage during such spacing movement.

125

130

135

10. The combination in a dictation machine of a frame, a carriage movably mounted on said frame, a record support, a stylus on said carriage and free to move relative to said carriage, power operated means for spacing said carriage along the frame and the record support, and means actuated by said power-operated means positively to prevent free movement of the stylus relative to said carriage during such spacing movement.

140

145

11. In a phonograph, in combination, a stylus, a sound-box, a stylus support pivotally mounted in the sound-box to permit the stylus to have free tracking movement, a sound-box carriage, automatic backspacing means to move the car-

150

- riage step by step, means pivotally mounted on the carriage adjacent the sound-box and adapted to engage said stylus mounting means to hold the stylus against free tracking movement, and 5 other means pivotally mounted on said carriage adapted to be actuated by said backspacing means when it is operated and to engage and render effective said holding means to prevent free tracking movement of said stylus.
- 10 12. In a dictation machine, the combination of a support for a record, sound reproducing means comprising a stylus mounted for free lateral movement and adapted to track the record, motive means for actuating said support, means actuatable by said motive means to shift said stylus back toward the beginning of the record, and means also actuatable by said motive means for ensuring proper positioning of the stylus with respect to its mounting when the same is so shifted, substantially as described.
- 15 13. In a phonograph, the combination of a support for a record, sound reproducing means comprising a stylus mounted for free lateral movement and adapted to track the record, motive 20 means for actuating said support, means comprising a ratchet device actuatable by said motive means and adapted upon each actuation thereof to shift said stylus a predetermined distance back toward the beginning of the record, and means also actuatable by said motive means for ensuring the proper positioning of the stylus with respect to its mounting when so shifted, substantially as described.
- 25 14. In a phonograph, the combination of a support for a record, sound reproducing means comprising a stylus mounted for free lateral movement and adapted to track the record, motive 30 means for actuating said support, means actuatable by said motive means to shift said stylus back toward the beginning of the record, and means also actuatable by said motive means for
- 35 preventing any free movement of the stylus with respect to its mounting, when the same is so shifted, substantially as described.
- 40 15. In a phonograph, in combination, a record-support, means for operating said record-support, a carriage, a stylus mounted on said carriage and capable of universal movement with respect to said carriage whereby said stylus has free tracking movement with respect to said record-support, means operable by said record-support operating means for spacing said carriage relative to said record-support, means for lifting said stylus from a record on said record-support, means for holding said stylus against free movement in one plane relative to the carriage when said carriage is moved by said spacing means and also when said stylus is lifted by said lifting means, and means for centralizing said stylus with respect to said carriage, when said stylus is lifted from said record, said holding means being adapted to yield and permit the centralizing of said stylus. 80
- 45 16. In a phonograph, in combination, a record-support, a carriage movable longitudinally of said record-support, a stylus associated with said carriage and having universal movement with respect to said carriage, said stylus being adapted to engage the surface of a record on said record-support, means for back-spacing said carriage while said stylus engages the surface of said record, means for holding said stylus against movement in one plane relative to said carriage when said stylus is backspaced over said record, said means being sufficient to overcome the friction between the stylus and record, but permitting of universal movement of said stylus when a force is applied to said stylus which is greater than the friction existing between the stylus and said record. 90

CERTIFICATE OF CORRECTION.

Patent No. 1,983,039.

December 4, 1934.

JOSEPH M. LUCARELLE, ET AL.

It is hereby certified that error appears in the printed specification of the above numbered patent requiring correction as follows: Page 4, line 136, claim 10, and page 5, line 10, claim 12, for "dictation machine" read phonograph; and that the said Letters Patent should be read with these corrections therein that the same may conform to the record of the case in the Patent Office.

Signed and sealed this 19th day of March, A. D. 1935.

(Seal)

Leslie Frazer
Acting Commissioner of Patents.

- riage step by step, means pivotally mounted on the carriage adjacent the sound-box and adapted to engage said stylus mounting means to hold the stylus against free tracking movement, and 5 other means pivotally mounted on said carriage adapted to be actuated by said backspacing means when it is operated and to engage and render effective said holding means to prevent free tracking movement of said stylus.
- 10 12. In a dictation machine, the combination of a support for a record, sound reproducing means comprising a stylus mounted for free lateral movement and adapted to track the record, motive means for actuating said support, means actuatable by said motive means to shift said stylus back toward the beginning of the record, and means also actuatable by said motive means for ensuring proper positioning of the stylus with respect to its mounting when the same is so shifted, substantially as described.
- 15 13. In a phonograph, the combination of a support for a record, sound reproducing means comprising a stylus mounted for free lateral movement and adapted to track the record, motive 20 means for actuating said support, means comprising a ratchet device actuatable by said motive means and adapted upon each actuation thereof to shift said stylus a predetermined distance back toward the beginning of the record, and means also actuatable by said motive means for ensuring the proper positioning of the stylus with respect to its mounting when so shifted, substantially as described.
- 25 14. In a phonograph, the combination of a support for a record, sound reproducing means comprising a stylus mounted for free lateral movement and adapted to track the record, motive 30 means for actuating said support, means actuatable by said motive means to shift said stylus back toward the beginning of the record, and means also actuatable by said motive means for
- 35 preventing any free movement of the stylus with respect to its mounting, when the same is so shifted, substantially as described.
- 40 15. In a phonograph, in combination, a record-support, means for operating said record-support, a carriage, a stylus mounted on said carriage and capable of universal movement with respect to said carriage whereby said stylus has free tracking movement with respect to said record-support, means operable by said record-support operating means for spacing said carriage relative to said record-support, means for lifting said stylus from a record on said record-support, means for holding said stylus against free movement in one plane relative to the carriage when said carriage is moved by said spacing means and also when said stylus is lifted by said lifting means, and means for centralizing said stylus with respect to said carriage, when said stylus is lifted from said record, said holding means being adapted to yield and permit the centralizing of said stylus. 80
- 45 16. In a phonograph, in combination, a record-support, a carriage movable longitudinally of said record-support, a stylus associated with said carriage and having universal movement with respect to said carriage, said stylus being adapted to engage the surface of a record on said record-support, means for back-spacing said carriage while said stylus engages the surface of said record, means for holding said stylus against movement in one plane relative to said carriage when said stylus is backspaced over said record, said means being sufficient to overcome the friction between the stylus and record, but permitting of universal movement of said stylus when a force is applied to said stylus which is greater than the friction existing between the stylus and said record. 90
- 50 100

CERTIFICATE OF CORRECTION.

Patent No. 1,983,039.

December 4, 1934.

JOSEPH M. LUCARELLE, ET AL.

It is hereby certified that error appears in the printed specification of the above numbered patent requiring correction as follows: Page 4, line 136, claim 10, and page 5, line 10, claim 12, for "dictation machine" read phonograph; and that the said Letters Patent should be read with these corrections therein that the same may conform to the record of the case in the Patent Office.

Signed and sealed this 19th day of March, A. D. 1935.

(Seal)

Leslie Frazer
Acting Commissioner of Patents.
